United States Patent Office.

JOHN GOODIN, OF CENTRALIA, ILLINOIS.

Letters Patent No. 82,513, dated September 29, 1868.

IMPROVEMENT IN WRENCH.

The Schedule referred to in these Letters Patent and making part of the same.

TO ALL WHOM IT MAY CONCERN:

Be it known that I, JOHN GOODIN, of Centralia, in the county of Marion, and in the State of Illinois, have invented a certain new and useful Improvement in Wrenches; and do hereby declare that the following is a full, clear, and exact description thereof, reference being had to the accompanying drawings, and to the letters of reference marked thereon.

The nature of my invention consists in the use of a cam-wheel, for tightening the jaws on a wrench, which wrench is so constructed that it can be used for gas-pipes and other purposes.

In order to enable others skilled in the art to which my invention appertains to make and use the same, I will now proceed to describe its construction and operation, referring to the annexed drawings, which form a part of this specification, and in which—

Figure 1 is a perspective view of the wrench, and

Figure 2 is a perspective of a lever, which may be used to tighten the jaws of the wrench.

A represents a bar, of suitable material and length, which passes through the handle, B, and is fastened at its lower end by a nut, C, as shown in fig. 1.

On the upper end of the bar A, the jaw D is firmly secured, and the jaw E, which is slotted, slides up and down on the said bar. On one side of the bar A, the jaws D and E are formed as usual in wrenches, but on the other side they are grooved out, forming, when put together, a round hole, the surface of which grooves is corrugated, as shown, whereby the wrench becomes adapted to firmly hold pipes for any purposes desired, and to turn round nuts as well as those with square sides.

The movable jaw E is provided with two arms, a a, on its lower side, which arms slide along the edges of the bar A, and are connected at their lower ends by cross-pieces, b b. On the side of the bar A is pivoted a cam-wheel, F, which operates on the lower side of the movable jaw E, moving the same upwards against the stationary jaw D. A pawl, d, on one of the cross-pieces b, fits into notches on the side of the cam-wheel F, thus holding the movable jaw E at any point desired. A spring, e, presses against the pawl d, preventing its escape from the said notches unless pressed down by the operator.

The cam-wheel F is cut with a square hole through it, as seen in the drawings, and in this hole the upper end of the lever G is inserted, the more easily to turn the cam-wheel F, and tighten the jaws. The lower end of the lever G is formed so as to answer for a screw-driver, but said lever may be entirely dispensed with, if desired.

It will be seen that after tightening the jaws by means of the cam-wheel F, it is not necessary to remove the pawl d and turn the wheel backward, but keep on turning the wheel the first way, and it will work against the cross-piece b, separating the jaws.

Having thus fully described my invention, what I claim as new, and desire to secure by Letters Patent, is—

The arrangement of the notched cam-wheel F, pawl d, spring e, for the purpose of adjusting the movable jaw on a monkey-wrench, constructed and operating substantially as herein set forth.

In testimony that I claim the foregoing, I have hereunto set my hand, this 18th day of July, 1868.

JOHN GOODIN.
